UNITED STATES PATENT OFFICE

ROBERT S. BLAIR, OF STAMFORD, CONNECTICUT

CASE FOR TOILET ARTICLES AND THE LIKE

Application filed April 14, 1928. Serial No. 269,960.

This invention relates to portable cases for toilet articles and the like.

One of the objects thereof is to provide a practical device of the above nature of simple and compact construction. Another object is to provide a device of the above nature characterized by efficient action and convenience in use. Other objects are to provide a device of the above nature which shall be readily adaptable to various numbers and types of articles, which shall hold them securely and yet in a readily accessible position and which shall so dispose of them as to economize space. Other objects will be in part obvious or in part pointed out herein-after.

The invention accordingly consists in the features of construction, combinations of elements and arrangements of parts, all as will be illustratively described herein, and the scope of the application of which will be indicated in the following claims.

In the accompanying drawing in which is shown one of various possible embodiments of this invention,

Figure 1 is a perspective view showing the case open in condition for use;

Fig. 2 is a diagrammatic side elevation of the case closed;

Fig. 3 is a similar view showing the case open;

Fig. 4 is an end elevation in semi-diagrammatic form of the case open;

Fig. 5 is a sectional view taken along the line 5—5 of Fig. 1;

Fig. 6 is a side elevation of a portion of the casing in open form certain parts being broken away to show the construction more clearly; and

Fig. 7 is a detailed sectional view on an enlarged scale of a supporting member.

Similar reference characters refer to similar parts throughout the several views of the drawing.

Referring now to Fig. 1 of the drawing,

there is shown a casing comprising two sections 10 and 11. Section 10 comprises an end wall 12 of substantial height and an end wall 13 of lesser height, these parts being preferably connected by the bottom 14 formed integral therewith. In the preferred embodiment of this invention the member comprising parts 12, 13 and 14 may be formed of sheet metal flanged upon all of its free edges as indicated at 15.

Section 11 comprises an end wall 16 of the same height as the end wall 13 and an end wall 17 substantially shorter, these end walls being connected by an integral bottom member 18 and all free edges being flanged as indicated at 19. Thus the end and bottom members of sections 10 and 11 are similar except that the end wall 12 is substantially higher or longer than the end walls 13 and 16 and the end wall 17 is substantially shorter than these latter walls, the proportions being such that the total length or height of walls 12 and 17 is equal to the total height of walls 13 and 16.

Wrapped about and secured to these flanged metal members is a leather covering. The point of attachment of this covering to the flanges of the sections 16 and 17 begins at a substantial space below their upper ends as indicated at 20, and the leather of which the covering is formed is preferably creased as at 21 so as to readily fold down as indicated in Fig. 1. This portion of the covering, aside from the section 22 just referred to, has an extension 23 connected along the creased line 24 and so shaped as to fold over and cover the uppermost flanges of the end walls 16 and 17 and thus provide a removable cover for the section 11.

The leather cover member being preferably stitched through perforations in the various flanges, is secured to the side, bottom and rear side flanges of the walls 16 and 17 up to the points 25 and there provided with a crease 26 to permit bending along a horizon-

tal line, it being understood that the creases 21 and 24 are preferably inclined with respect to the horizontal. From the crease 26 the cover extends to a parallel crease 27 so positioned that it will with the casing in closed form be substantially opposite the upper edge of the sections 13 and 16. The continuation of the cover passes through to a crease 28 from which point it is secured to the adjacent flanges of the end walls 12 and 13 of section 10 and follows these flanges stitched thereto around to the point 29 at which another crease is provided, this crease being inclined so as to meet the adjacent flange of end wall 13 at the same distance beneath its top as it meets the adjacent flange of the end wall 12 thus forming another loose side wall portion 30. The end part or flange of the cover 31 is adapted to overlie the portion 22 with the case in closed form as herein-after described and is provided with a strap 32 coacting with a buckle 33 or suitable securing device.

In order that the features of construction thus far described may be best understood, it may be noted that when it is desired to close the case the part 22 is folded against the adjacent flanges and part 23 laid over the top of section 11. The two sections are then pushed together so as to bring the intermediate wall portions 34 and 35 into upright position, and the entire section 11 is then swung over section 10. The flap 31 is then raised and secured in position as by the buckle 33. The entire case will then have changed from the form shown in Figs. 3 and 4 of the drawing to the form shown in Fig. 2 in which it is substantially rectangular, the two sections being complementary one to the other.

Within section 10 there is provided a supporting member 36 which is of considerable length and tapering from its greatest height adjacent end wall 12 to a minimum height adjacent end wall 13. This member is formed of bendable sheet metal as indicated at 37 in Fig. 7 of the drawing and has upon its opposite sides a soft coating as of rubber or of fabric cemented thereto as indicated at 38. The member 36 is readily bent into any desired shape so as to accommodate the desired number and shape of articles to be held and is slipped into place within the section 10. It may readily be removed as for purposes of cleaning the case, but ordinarily it serves merely to support securely and in upright form the various toilet articles.

In section 11 is a similar member 39 tapering from a maximum height adjacent end wall 16 to a minimum height adjacent end wall 17 and also bendable into any desired shape.

In the use of the device it will be seen that when it is open it occupies a minimum of space and may readily be placed upon the side of a wash basin of a Pullman car for exam-

ple. All articles, furthermore, although securely held in position, are readily accessible and compactly disposed. There is provided means for supporting articles varying in length from the substantial height of end wall 12 to the small height of end wall 17. The casing is quickly and conveniently closed as hereinbefore described, and when closed adopts the rectangular form shown with a maximum of compactness. It will be seen, furthermore, that there is no tendency for the articles to slip out of the case either when the casing is open or closed and that the construction is simple and strong and not adversely affected by hard practical use.

As many possible embodiments may be made of the above invention, and as many changes might be made in the embodiment above set forth, it is to be understood that all matter hereinbefore set forth or shown in the accompanying drawing is to be interpreted as illustrative and not in a limiting sense.

I claim:

1. In a portable hollow case for implements of varying size and contour, in combination, a plurality of sections each comprising a bottom and a plurality of walls extending away from said bottom and held in a position to embrace a space and each of substantially uniform depth in the direction of its shortest transverse dimension and of varying depth in the direction of its other transverse dimension, and each of said sections having an open end, means connecting said sections one to the other to permit their open ends to swing together to close the case, and holding means positioned within each of said sections within the planes of the open ends thereof and shaped to removably hold articles of different shapes in a position extending toward the corresponding open ends.

2. In a portable hollow case for implements of varying size and contour, in combination, a plurality of elongated sections each comprising a bottom and a plurality of walls extending away from said bottom and held in a position to embrace a space and each tapering lengthwise from end to end and each provided with an open end, means connecting said sections to permit them to rest substantially upright upon the same supporting surface, and means adapted to support articles in at least one of said sections in position for removal endwise through the open end thereof.

3. In a portable hollow case for implements of varying size and contour, in combination, a plurality of complementary sections, each having lateral walls held in position to embrace a space of progressively increasing depth and the average depth of one being greater than the average depth of the other, said sections being elongated in the direction of their variation in depth and being shaped to form a parallelogram when in

closed position with their open ends together.

4. In a portable hollow case for implements of varying size and contour, in combination, a plurality of complementary sections each comprising a bottom, sides and unequal ends and each of progressively increasing depth and the average depth of one being greater than the average depth of the other, said sections being elongated in the direction of their variation in depth and being shaped to form a parallelogram when in closed position with their open ends together, said sections being connected to permit them to swing about an axis substantially parallel to their bottoms and being shaped to rest side by side upon a supporting surface with their open ends upward.

5. In a portable hollow case for implements of varying size and contour, in combination, a plurality of sections, each having a substantially flat bottom and lateral walls shaped and held to embrace a space and each tapering in depth transversely, holding means in each of said sections adapted to support articles of different shapes in position to be removed endwise in a direction away from the bottom, and means connecting said sections one to the other to permit them to be placed in a position side by side with their bottoms resting upon the same supporting surface.

6. In a portable hollow case for implements of varying size and contour, in combination, a plurality of sections, each comprising a pair of end walls and a continuous cover member extending about all of said end walls and secured thereto at their side edges and spaced thereby and forming a hinge whereby the sections may be swung into a closed position with their open ends together and into an open position in which they rest side by side upon a supporting surface, and means adapted to secure in place the free end of said cover member and thereby hold said sections together.

7. In a portable hollow case for implements of varying size and contour, in combination, a plurality of sections, each comprising a pair of end walls and a bottom, means forming side walls for each of said sections and connected with said end walls throughout a portion of their lateral edges, being free from such edges at the portions of the end walls remote from the corresponding bottoms, said sections being shaped to provide open tops of substantially the same size and shape adapted substantially to register with the case in closed condition and means adapted to hold articles of different shape and size in predetermined positions within said sections.

8. A receptacle for containing a variety of articles for personal use differing as to size and contour, and a member in said receptacle so shaped as to provide a plurality of com-

partments directed toward the open end of the receptacle and formed of a material of such characteristics as to permit easy deformation thereof to change the size and shape of the different compartments and to retain the form into which it is bent.

9. A receptacle for containing a variety of articles for personal use differing as to size and contour, and a member in said receptacle so shaped as to provide a plurality of compartments directed toward the open end of the receptacle and formed of a material of such characteristics as to permit easy deformation thereof to change the size and shape of the different compartments and to retain the form into which it is bent, said receptacle being of varying depth in the direction of one of its transverse dimensions, and said holding member being removably mounted therein and formed of a sheet of varying depth to form said compartments of a depth substantially proportional to the depth of the receptacle at the point at which such compartment is positioned.

10. In a portable hollow case for implements of varying size and contour, in combination, a plurality of hollow sections, each provided with an open end, connected to swing into a position side by side with their open ends exposed and to swing into a closed position with their open ends together, said openings being of substantially the same size and shape and adapted substantially to register with the case in closed condition holding means in each of said sections adapted to support articles of different sizes and shapes in position to slide toward said open ends, and a movable partition between said open ends with the case in closed condition adapted to prevent the articles in each section from sliding into the other section.

11. In a portable hollow case for implements of varying size and contour, in combination, a plurality of hollow sections, each provided with an open end, connected to swing into a position side by side with their open ends exposed and to swing into a closed position with their open ends together, said openings being of substantially the same size and shape and adapted substantially to register with the case in closed condition holding means in each of said sections adapted to support articles of different sizes and shapes in position to slide toward said open ends, and a movable partition between said open ends with the case in closed condition adapted to prevent the articles in each section from sliding into the other section, said sections being of progressively increasing depth in the direction of one of their transverse dimensions, and said partition having a swinging connection upon the case.

12. In a portable hollow case for implements of varying size and contour, in combination, a plurality of hollow sections, each

comprising a pair of end walls and a bottom formed of metal and a continuous non-metallic cover member extending about said bottoms and secured to said end walls to provide
6 a connection whereby said sections may be swung with respect one to the other, and means adapted to secure the free end of said non-metallic cover member to another portion thereof to hold the case in closed condition
10 with the open ends of the sections together.

In testimony whereof, I have signed my name to this specification this 13th day of April, 1928.
